PAPER PULP EXTRACTOR

Lemuel V. Reese and George W. Johnson, Cincinnati, Ohio, assignors to The American Laundry Machinery Company, Cincinnati, Ohio, a corporation of Ohio

Original application March 2, 1931, Serial No. 519,443. Divided and this application November 30, 1931. Serial No. 577,970

3 Claims. (Cl. 92—34)

Our invention relates to centrifugal extractors and, particularly, to an apparatus embodying centrifugal action for freeing paper pulp from impurities according to the specific gravity of the 5 impurities, and delivering the paper pulp in a purified state to the paper making machines. This application is a division of our application Ser. No. 519,443, filed March 2, 1931, issued as Patent No. 1,887,955, of November 15, 1932, for 10 a Paper pulp extractor.

Centrifugal machines of this character usually embody a rotatable basket having a solid wall with means provided thereon for retarding the normal tendency of the pulp to flow upwardly in 15 order to subject the pulp to centrifugal action over such period of time that the impurities and pulp will be separated and a skimming ring that is employed for skimming off the lighter weight impurities forming the inner stratum of the mass 20 within the basket, the purified pulp made up of fibres only forming the center stratum and being delivered continuously into a volute as untreated pulp is fed into the basket. It is well understood that centrifugal action divides the mass up into 25 the heavier stratum or those parts having the greatest specific gravity, an intermediate stratum which is normally the purified paper pulp, and an inner stratum made up of impurities of less specific gravity than the paper pulp. In previous 30 machines, the skimmer ring, while functioning to skim off the lighter weight impurities has embodied no means for holding such impurities, the impurities finally overflowing at the inner edge 35 of the skimmer ring into the volute or delivery conduit to intermingle with the purified stock and flow outwardly therewith.

It is the object of our invention to provide a means for trapping the lighter weight impurities that form the inner stratum of the layer of pulp 40 being purified as well as a means for filtering out the impurities under centrifugal force and permitting the water intermingling with them to flow over into or be thrown outwardly by centrifugal force into the purified pulp in the volute, 45 thus finally delivering completely purified pulp having the proper water content.

Various other objects and advantageous features will be seen in the following description and one embodiment thereof may be seen in the accompanying drawing wherein similar characters of reference designate corresponding parts, and 50 wherein:

Fig. 1 is a view, partly in section and partly in elevation, showing an apparatus constructed in 55 accordance with our invention; Fig. 2 is a top

plan view of the apparatus shown in Fig. 1 with the power unit and supporting means therefor removed; and Fig. 3 is a sectional view showing the position taken by the various stratum having different specific gravities during the operation 60 of the apparatus and the delivery of the purified stratum to the volute.

Referring to the drawing, we have shown a centrifugal extractor consisting of the usual curb 1 supported by suitable base members 2 and 65 adapted to receive a rotatable basket 3 mounted on a spindle 4 that rotates in a bearing 5 carried by the curb 1 and has its opposing end attached to the drive shaft 6 of the suitable motor or power means 7. As shown, this motor or power means 70 is pivotally mounted in a pivoted gimbal ring 8 supported by suitable uprights 9 which will permit precession of the spindle 4 during operation of the apparatus.

As is customary in such apparatus, suitable 75 circumferential baffle flanges 10 are disposed within the basket 3 for the purpose of retarding the upward flow of pulp and also for building up a pulp mat into which the heavy impurities 80 extracted from the pulp during the centrifugal operation of the basket will be imbedded and thereby retained in the basket. The top of the basket is provided with an annular ring 11 having an overhanging portion 12 adapted to retain the pulp 85 mat and heavier impurities and prevent their flow out of the basket and an overhanging portion 13 that acts as a guide for directing the extracted paper pulp into a volute 14 and as a means for preventing the paper pulp from falling 90 downwardly between the curb and the basket.

In accordance with our invention, a vertically 95 extending annular skimmer ring 15 is provided at the upper end of the basket and is spaced a sufficient distance from the innermost edges of the overhanging portion 12 to skim off or separate the lighter impurities from the paper pulp. An annular screen or filter means 16 extends vertically upwardly from the skimmer ring 15 and is of such nature as to have filtering qualities sufficient to hold all impurities and permit the 100 passage of clarified liquid therethrough and over into the volute 14, the liquid being separated and thrown outwardly by centrifugal action. The curb 1 is shown as being provided with a suitable cover 17 although this is not absolutely essential.

In the operation of the apparatus, wood pulp from the usual beaters is fed into the basket 3 through a pipe 18 which has its outlet opening 110 near the bottom of the basket. Then, the basket

is rotated at a speed which will produce a centrifugal force effective on impurities heavier than the weight of the fiber in the pulp to cause them to be imbedded in a mat of fiber formed on the inner periphery of the basket wall and between the circumferential flanges 10 as shown at 19 in Fig. 3 while a stratum of purified fiber will form adjacent the mat of fiber containing the heavier impurities as shown at 20, this stratum of fiber tending to move upwardly as the pulp is fed into the basket. Speed of rotation of the basket is such that the impurities of the lighter weight than that of the paper pulp fibers are unaffected by the centrifugal action to the extent that they will rise by the action of flotation and with the stratum of pulp fibers 20, as untreated pulp is fed into the basket forming an inner stratum that is skimmed off by the skimming ring 15 and pushed upwardly on the surface of the screen or filter 16. The centrifugal action will be effective on the lighter impurities to separate the water therefrom and throw the water outwardly into the volute 14 into which the stratum 20 of the purified paper pulp fiber passes. Thus, a means is provided for purifying the paper pulp by removing both the heavier and the lighter impurities therefrom by centrifugal action, while, at the same time, not forever alienating the normal water content from the pulp whereby the purified pulp will be delivered from the delivery end 22 of the volute 14 with the proper water content. This is a highly advantageous and very desirable feature.

What we claim is:

1. The process of refining paper pulp which comprises subjecting pulp to centrifugal action to separate the pulp and impurities into strata whereby pulp free of impurities may be had, separating and trapping the impurities, extracting liquid from such impurities, and delivering such liquid to the purified pulp. 80

2. The process of refining paper pulp which comprises subjecting pulp to centrifugal action to separate the pulp and impurities into strata whereby pulp free of impurities may be had, separating and trapping the impurities, extracting liquid from such impurities by the same centrifugal action that separates the pulp and impurities into different strata, and delivering such liquid to the purified pulp. 85

3. The process of refining paper pulp which comprises subjecting pulp to centrifugal action to separate the pulp and impurities into stratum namely, a strata of light impurities, a strata of purified pulp, and a stratum of heavy impurities whereby pulp free of impurities may be had, trapping the heavier impurities and the lighter impurities while delivering pulp free of impurities, extracting liquid from the lighter impurities by centrifugal action, and delivering such liquid to the purified pulp. 90
